United States Patent Office.

GEORGE F. WRIGHT AND WILLIAM ORR, JR., OF CLINTON, MASSACHUSETTS.

Letters Patent No. 79,287, dated June 23, 1868; antedated June 5, 1868.

IMPROVEMENT IN TAGS.

The Schedule referred to in these Letters Patent and making part of the same.

TO ALL WHOM IT MAY CONCERN:

Be it known that we, GEORGE F. WRIGHT and WILLIAM ORR, Jr., of Clinton, county of Worcester, and State of Massachusetts, have invented a new and useful Mode of Fastening Strings, Thread, or Wire in Direction-Tags or Labels; and we do hereby declare that the following is a full and exact description thereof, reference being had to the accompanying drawings, and to the letters of reference marked thereon.

The nature of our invention consists in the use of a piece of pasteboard, or any suitable material whose thickness corresponds with the diameter of the string, or its equivalent, inserted into the loop of said string, and pasted or glued between the tag and the heading-piece, thus uniting the whole together to form a smooth and firm combination.

Figure 1 is a perspective view of a tag all complete. Red lines indicate what is covered by the heading-piece glued down upon it.

Figure 2 is a view of a tag in the same position, with the heading-piece lifted up, showing the string-loop passed through the small hole in the tag, and the piece of pasteboard inserted, before the heading is glued and turned down upon it.

Figure 3 represents a circular piece of pasteboard, or its equivalent.

Figure 4 is an edge view of same.

Figures 5, 6, 7, and 8 are views of different-shaped pieces of pasteboard, or its equivalent, which may be used.

a *a*, in fig. 1, is the string, attached to the tag or label by passing into the small hole, and around the pasteboard *b*, or its equivalent, (as shown by the red lines,) and out at the same hole.

b is a piece of pasteboard, or its equivalent, glued in with the string, thread, or wire, between the heading and body of the tag.

c, in fig. 2, is the lap or a piece of the end of the tag, which is to be covered with glue or some adhesive material, and turned over, so as to cover the piece of pasteboard *b*, and the loop of the string *a*, to form a heading to the tag, which shall be so firm and solid as to render it impossible to draw the string out.

Having thus described our invention, what we claim as new and useful, and desire to secure by Letters Patent, is—

The use of a circular or otherwise-shaped piece of pasteboard, or its equivalent, when inserted between the two thicknesses of the tag or label, around which the string, or its equivalent, is looped, in the manner substantially as herein shown and described.

GEORGE F. WRIGHT,
WILLIAM ORR, JR.
